HARDWARE PACKAGE AND DISPLAY

Rome C. Seyforth, Shelby, Ohio, assignor to The
Shelby Metal Products Company, Shelby, Ohio,
a corporation of Ohio

Application January 21, 1953, Serial No. 332,384

4 Claims. (Cl. 206—80)

1

The present improvements relating as indicated to hardware packages have more particular regard to packages of this sort designed for displaying functionally cooperative articles of small hardware, such as household hardware, in number and kind sufficient to provide complete sets as required for different applications thereof.

This type of display packaging has been found highly successful, especially where the articles are mounted in neat and pleasing arrangement on a flat display card, since all the items necessary for a particular intended job may readily be handled, inspected and sold as a unit. As a result, it is now common for cabinet catches and hinges, drawer or door pulls and catches, window hardware, and the like, to be put up in job-suited packages; for example, a package designed for use in mounting a cabinet door may include two hinges, a catch, and screws in number needed to secure the same to the door, all suitably mounted on a display card.

It is desirable to provide complete display sets of this nature for as many of the household hardware applications as possible, however, certain jobs, notably the installation of a screen door, require an elongated coil spring, and, heretofore, no display package has been available for conveniently mounting such a spring together with the hinges, pull, hooks and screws also used. These springs, therefore, continued to be boxed loose, and required to be individually sorted by the clerk and given to a prospective purchaser.

The invention, accordingly, has as a principal object the provision of a display mounting for an elongated flexible spring wherein the spring is flexed to reduce the effective length thereof and attached to a display card in this condition. It is also an object of the invention to mount an elongated spring in this fashion with a minimum of attaching means interengaging the spring and card. A further object is to provide a display package for hardware including a loop-type handle, such as a screen door handle, and an elongated flexible spring wherein the handle is utilized to hold the spring against a display card. Other objects and advantages will become apparent as the following description proceeds.

To the accomplishment of the foregoing and related ends, the invention, then, comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

2

In said annexed drawing:

Fig. 1 is a front plan view of a display package in accordance with my invention wherein the hardware required for installation of a screen door is mounted on a flat display card;

Fig. 2 is a rear view of such package showing the arrangement of the fastening means used to secure the hardware to the card;

Fig. 3 is a top edge view of the package, this view being indicated by the line 3—3 in Fig. 1.

Referring now to the drawing in detail, my invention is there shown, for purposes of illustration only, as applied to the packaging of a screen door set comprising a pair of hinges 10, a door handle 11, an elongated coil spring 12, and a small bag 13, of plastic or other suitable material, within which the screws, hooks and eye required to attach these articles to the door are contained.

This hardware is arranged on a flat display card 14 which has a face portion 15 and is provided with a plurality of apertures for the reception of article fastening means. In order that printed matter may appear on both sides of the card, it is preferred that the card be made as an elongated blank having a finished surface adapted to receive the printing desired, the blank being folded lengthwise to form the card with the finished and printed blank surface outward of the fold. Folding the card in this manner, of course, additionally serves to improve the rigidity thereof. Hinges 10 are arranged in side-by-side relation on the face portion 15 of the card, and apertures 16 are disposed to correspond with the outer aligned openings of each hinge plate. Passing through the openings 16 from the rear of the card are metallic, generally U-shaped, clasps 17, the end portions 18 of which are bent inwardly over the hinge plates after passing through the openings therein. The handle 11 is secured to the card in similar manner by means of a further clasp 19 extending through card apertures 20 arranged in registering relation with the openings 21 in the respective ends of such handle. As shown, the thus secured handle projects outwardly from face portion 15 of the card and extends generally at right angles relative to and above the mounted hinges.

The small bag 13, containing the screws and other fastening elements, is suitably attached to the card under the mounted handle, for example, by stapling. This bag is preferably of such size that it will lie generally flat beneath the handle, as shown, and overlie the upper hinge portions. It will be apparent that the arrangement thus far described efficiently utilizes

the card area to maximum extent, presenting the hardware in neat and pleasing manner.

In accordance with my invention, the elongated coil spring 12 is also secured wholly within the confines of the card, and, to this end, a further opening 22 is located in the lower card portion centrally of the openings 20 used to attach the handle. This further opening lies between the mounted hinges 10 and is adapted to receive a metal clasp 23, of general staple form, having outwardly flaring end portions 24 engaging the rear card surface. Thus, clasp 23 projects from the same card face as does handle 11.

Since the normal spring length is greater than the card extent, spring 12 is flexed to form two side-by-side loops and attached to the card in this condition. This is achieved by first placing the spring on the card with the central portion 25 thereof overlying hinges 10 between opening 22 and handle 11 in parallel relation to the latter. The respective spring end portions 26 are next looped inwardly to the remote side of handle 11 and passed therethrough across bag 13 and central spring portion 25 until end rings 27 are located above opening 22. Staple clasp 23 is then passed through rings 27 and opening 22 and its end portions 24 flared as shown. The spring is, therefore, maintained in generally flat looped condition by the cooperative action of handle 11 and clasp 23, with the central spring portion 25 being restrained from outward movement relative to the card by the crossing thereover of spring end portions 26. Likewise, the spring overlies and holds bag 13 against the card, thereby protecting against the bag being torn from the card in handling.

As a result of the described packaging, all necessary articles for mounting a screen door, including the unwieldy spring, are presented as a complete set in a package particularly suited for display purposes. While the set described in detail is designed for screen door use, it is obvious that elongated springs may also be attached to display cards in the manner set forth either alone or with other hardware articles, and if the hardware to be displayed does not include a loop-type door handle, a loop clasp or equivalent fastening means may be utilized in place of such handle.

Other modes of applying the principle of the invention may be employed, change being made as regards the details described, provided the features stated in any of the following claims, or the equivalent of such, be employed.

I therefore particularly point out and distinctly claim as my invention:

1. A hardware display package comprising a loop-type door handle, a coiled door spring, a dis-

play card having a face portion, means operative to secure said handle to said card with the loop thereof projecting outwardly from said face portion, an opening in said card spaced from the 5 thus secured handle intermediate the ends thereof, the central portion of said spring being disposed on said card between said handle and said opening, the end portions of said spring being looped respectively inwardly to the remote side of 10 said handle and passed therethrough and across said central spring portion, and clasp means attached to said card through said opening operative to engage the ends of said spring, whereby the spring will be maintained in looped condition 15 on said card by the cooperative action of said handle and said clasp means.

2. A hardware display package comprising a coiled door spring, a display card having a face portion, a loop member secured to said card and projecting outwardly from said face portion, the 20 central portion of said spring being disposed on said card to one side of said loop member, the end portions of said spring being looped respectively inwardly to the opposite side of said loop member and passed therethrough and across said central spring portion, and clasp means interengaging the end portions of said spring and said card on the side of said central spring portion removed from said loop member.

3. A hardware display package comprising a coiled door spring, a display card, said spring being disposed on said card in the form of two loops arranged in side-by-side relation with the 25 respective end portions thereof overlying the central spring portion, first attaching means carried by said card operative to engage the looped portions of said spring, thereby to hold the same against said card, and second attaching means 30 interengaging the spring end portions and said card on the side of such central spring portion opposite that of said first attaching means.

4. A hardware display package comprising a coiled door spring, a display card upon which 35 said spring is disposed in the form of two loops arranged in side-by-side relation with the respective end portions thereof overlying the central spring portion, readily detachable means interengaging the upper portions of the spring loops and the card, and means likewise readily detachable interengaging the end portions of the 40 spring and the card, thereby to maintain the spring in such looped condition on said card.
